UNITED STATES PATENT OFFICE.

FRANK W. HARRISON, OF MORRISON, TENNESSEE.

HARROW.

No. 880,301.

Specification of Letters Patent.

Patented Feb. 25, 1908.

Application filed June 26, 1907, Serial No. 380,951.

To all whom it may concern:

Be it known that I, FRANK W. HARRISON, a citizen of the United States of America, residing at Morrison, in the county of Warren 5 and State of Tennessee, have invented new and useful Improvements in Harrows, of which the following is a specification.

This invention is an improved flexible harrow in which the bars are flexibly connected 10 together for movement independently of one another, and in which a harrow is provided with improved means for adjusting such bars and the teeth carried thereby, to set the teeth at any desired angle and cause the teeth to 15 work in the soil at such angle, and the said invention consists in the construction, combination and arrangement of devices herein-after described and claimed.

Figure 1 is a top plan view of a harrow constructed in accordance with my invention. 20 Fig. 2 is a vertical longitudinal sectional view of the same. Fig. 3 is a detail rear elevation of the same. Fig. 4 is a detail sectional view of the same taken on the plane indicated by 25 the line *a—a* of Fig. 3.

In accordance with my invention I provide in connection with the beams 1 of a harrow, flexible means, such as chains 2, to connect such harrow beams together so that the 30 harrow beams may move independently of one another when passing over stones, stumps, roots or other obstructions and so that the harrow beams may be set at any desired inclination to cause the teeth 3 which 35 they carry to operate at such adjustment.

I here show only a single harrow section for the purpose of this specification. It will be understood, however, that my invention is applicable to harrows having a plurality of 40 sections, and it will also be understood that the harrow or each section thereof may have any suitable number of the beams.

The chains 2 are preferably in short lengths corresponding to the desired spaces between 45 the harrow beams, and they may be hooked or otherwise detachably secured to the harrow beams so that the latter may be disconnected from one another so that any desired number of the harrow beams may be used.

50 A draft chain 4 is shown connected to the front harrow beam. Each of the harrow beams is provided, preferably, at or near its center with an upwardly extending arm or standard 5. The said arms or standards are 55 connected by a chain or chains 6, which are shown as secured to the upper ends thereof so

that the said arms or standards, together with the several harrow beams to which they are secured will move in unison angularly when any one of them is thus moved. Each 60 of the said arms or standards is made of angle metal, providing a front web 13 and a side web 14. Such side web is shorter than such front web so that the upper end of the front web projects above such side web to form a 65 lug 15 for attachment of the chain, and such front web also projects below such side web to form a downwardly extending portion 16 which bears against the front side of the beam and is bolted thereto, the lower ends of 70 the said web forming a shoulder 17 which bears on the upper side of the beam.

An adjusting lever 7 has its lower end bolted, as at 18, to the side web of the arm 5 on the rear harrow beam 1, and such lever 75 has its lower portion bent obliquely, as at 19, with reference to such arm and is then extended vertically to form a space between such lever and such arm. A bolt 20 extends across such space and connects such lever to 80 the side web of such arm.

An adjusting and locking rod 9 has its front end pivotally connected, as at 10, to the front beam of the harrow, near or at the center thereof. Such adjusting and locking 85 rod is provided at its rear end with a handle 11 adapted to be conveniently grasped, and such rod is provided on one side near its rear end with rack teeth 12 to enable such rod to be engaged at any desired longitudinal 90 adjustment with the said bolt 20 which connects the adjusting lever 7 with the vertical arm or standard 5 of the rear harrow beam.

It will be understood that by first disengaging the adjusting and locking rod from 95 the adjusting lever and by then manipulating such rod and lever, the harrow beams may be adjusted to lie in a common horizontal plane or to assume any desired lateral inclination, and hence cause the teeth there- 100 of to be also so adjusted. By reengaging the rack portion of such adjusting and locking rod with the said lever the bars of the harrow may be locked at such adjustment.

A harrow thus constructed is exceedingly 105 strong and durable, is very light and flexible, may be adjusted to cause its teeth to operate in the soil at any desired angle, and since its bars are capable of moving independently of one another, such harrow is adapted to move 110 without injury to itself over obstructions in the field when at work. Furthermore, by

reason of the flexibility of the harrow the same accommodates itself to inequalities in the surface of the soil and performs its work more efficiently than is possible by harrows in which the beams are not capable of movement independently of one another.

Having thus described the invention, what is claimed as new, is:—

1. A harrow comprising bars having upwardly extending arms, each formed of angle metal providing a front web, a side web, the latter bearing on the bars and the front webs having downwardly extending portions secured to the front sides of said bars so that said side webs brace said angle metal arms, an adjusting lever also attached to one of said bars, means connecting such bars for angular adjustment, and an adjusting rod connected to one of such bars, such rod and 20 such lever having coacting means to connect such rod to such lever at any desired longitudinal adjustment of such rod, for the purpose set forth.

2. A harrow comprising bars having upwardly extending arms, one of such bars being also provided with an upwardly extending adjusting lever spaced from the arms of said bar, a bolt connecting such adjusting lever and said arm, means connecting such bars for angular adjustment, and an adjusting rod connected to one of such bars, such rod passing between such lever and the arm from which it is spaced and adapted to engage such bolt to connect such rod to such lever at any desired longitudinal adjustment of such rod, for the purpose set forth.

In testimony whereof, I affix my signature in presence of two witnesses.

FRANK W. HARRISON.
